NAIL MAKING MACHINE

José de Jesús Hernández, Guadalajara, Mexico

Application March 28, 1938, Serial No. 198,590
In Mexico February 28, 1938

3 Claims. (Cl. 140—130)

This invention relates to nail making machines and more particularly to an improved machine whereby a single hammer is capable of producing a plurality of nails with a single impact.

5 An object of this invention is to provide a multiple feed device for a nail or screw making machine whereby a plurality of wires or rods are fed into a position for engagement with the hammer so that a number of nails, screws, rivets, 10 tacks or the like are headed and otherwise formed by a single operation where in the past these articles were formed individually by providing a single feeding means for each strand or rod and also providing a separate hammer and cut-off 15 means for each article being formed by the machine.

Another object of this invention is to provide a device of this kind in the form of an attachment for a conventional nail or screw forming machine so that a number of articles such as nails or the 20 like may be formed by the single hammer, thus increasing the output of the machine without requiring a speeding up of the machine.

Another object of this invention is to provide a 25 multiple feed of this kind in the form of grooved wire or rod straightening rollers together with a pulling means associated with the rollers which is reciprocated back and forth so as to feed the several wire strands to the dies, and in this 30 manner, the capacity of the machine may be increased without the necessity of speeding up the movement of the operating parts of the machine.

A further object of this invention is to provide 35 an improved wire pulling means for an article forming machine in the form of a nail making machine so that different sizes of wire may be used with the same machine.

Still another object of this invention is to 40 provide an improved wire gripping means forming part of the wire pulling means so that the gripping means may be suitably tensioned against the wire passing through the pulling means.

To the above objects and others which may 45 hereinafter appear, the invention consists of the novel construction, combination and arrangement of parts as will be more specifically referred to and as illustrated in the accompanying drawings, wherein is shown an embodiment of the invention, but it is to be understood that changes, 50 variations and modifications may be resorted to which fall within the scope of the invention as claimed.

In the drawings:

Figure 1 is a detail side elevation partly in 55 longitudinal section of a device constructed ac-

cording to an embodiment of this invention mounted on the frame of a nail making machine, the frame being shown in fragmentary form,

Figure 2 is a detail top plan of the device shown in Figure 1,

Figure 3 is a sectional view taken on the line 3—3 of Figure 2,

Figure 4 is a sectional view taken on the line 4—4 of Figure 2,

Figure 5 is a fragmentary sectional view of one 10 of the operators for a wire gripper, and

Figure 6 is a fragmentary bottom plan of a slide and operator therefor.

Referring to the drawings, the numeral 10 designates generally the frame of a nail forming machine and in the present instance only the rear portion of the machine is disclosed where the wire enters the machine from the feed or supply roller. A hammer or nail head forming member 11 is connected to a reciprocating means 20 (not shown) and this hammer or head forming member 11 is reciprocated in a horizontal movement back and forth relative to a pair of clamping or die members 12. The die members 12 are connected to suitable means whereby these members may be moved transversely of the hammer 11 to a released position and moved toward each other to an operative or wire gripping position. The construction of the wire gripping or die members 12 is conventional and it is believed that 30 the operation of these members will be clearly understood by persons familiar with the art of nail or screw making.

At the present time it is the practice to feed a single wire strand or rod through the gripping or 35 die members 12 and the hammer 11 is then moved toward the die members 12 so as to upset the end of the wire and thus form a head on the end of the wire which later constitutes the head of a screw, nail, bolt, tack or the like. In the 40 machines at present in use, a separate hammer with individual die members 12 are provided for each strand of wire so that but a single nail or other article is headed and otherwise formed at each reciprocation of the hammer 11. In order to 45 provide a means whereby the capacity of a nail forming machine may be increased without the necessity of speeding up the operating parts of the machine, I have provided a plurality of rod or wire straightening rollers 14 which are rotatably secured on bolts 13 and which are secured to the frame portion 10 of the machine. These rollers 14 are provided in the present instance with a pair of spaced apart peripheral grooves 15 over which wire strands 16 pass. There are at 50 55

least three of these rollers 14, two of the rollers 14 being positioned as shown in Figure 2 on one side of the wire strands 16 in spaced apart relation and a third or intermediate roller 14 engages on the opposite side of the wire strands 16 in a position midway between the two outer rollers 14.

A wire pulling member generally designated as 17 is fixed to a slide plate 18 by means of bolts 19. The slide member 18 is provided at an intermediate point with a recess 20, and a rock arm or operating lever 21 is positioned in this recess 20 and is connected to a suitable crank means forming part of the machine so that the slide member 18 may be reciprocated back and forth on a guide 22 formed on the frame portion 10. A pair of segmental members 23 engage on opposite sides of the operating lever 21 and are seated in arcuate sockets 24 provided in the slide member 18. In this manner the operating lever 21 may be rocked back and forth in a horizontal movement and may move relative to the slide plate 18.

The pulling member 17 comprises a base plate 25 provided at the forward and rear ends thereof with upstanding flanges 26 and 27. These flanges 26 and 27 also extend downwardly over the opposite ends of the slide member 18 as shown at 28 and 29 so as to relieve the bolts 19 of strain due to the reciprocation of the pulling member 17 on the guide 22. The slide plate or base member 25 is provided with a pair of upstanding blocks or lugs 30 and 31 and a grooved wire guide member 32 secured as by a bolt 33 to the block 30. The guide member 32 is provided with a right angularly disposed leg or plate 34 engaging the outer side of the block or lug 30 and the bolts 33 pass through the leg 34. One of the wire strands 16 is adapted to pass through the groove in the upper side of the guide member 32 and the other wire strand 16 engages a grooved guide member 35. The guide member 35 is also provided with a right angularly disposed plate 36 which is fastened as by a bolt 37 to the block or lug 31. The groove in the guide member 35 is disposed in parallel relation to the groove in the guide member 32, but is offset vertically a distance equal to the space between the grooves 15 in the rollers 14. The upstanding flange 27 on base plate 25 is provided with a pair of guide openings 38 through which the wire strands 16 are adapted to pass. The upstanding flange 26 is also provided with a pair of holes or openings 39 axially aligning with the holes 38. The guide members 32 and 35 comprise stationary jaw members, the purpose for which will be hereinafter described.

A wire gripping member 40 is adjustably mounted in one leg of a bell crank lever 41 which is secured on a bolt 42 secured to the base plate 25. The gripping or clamping member 40 is adjustably secured in the bell crank 41 by means of a set screw 43 so that the lower or wire engaging end 44 thereof may project downwardly below the bell crank 41 sufficiently to engage a wire strand 16 passing over the stationary jaw or guide member 32. The opposite arm 45 of the bell crank 41 projects outwardly and is engaged by a spring pressed plunger 46 disposed in a housing 47. The plunger 46 may be tensioned by means of a tensioning nut 48 which engages against spring 49 disposed in the housing 47. The housing 47 is preferably formed integrally with the flange 27 and the base plate 25. The gripping member 40 is disposed on an oblique angle to the longitudinal axis of the wire strand

16 with one corner of the gripping member 40 slidably engaging the periphery of the wire strand 16. As viewed in the drawings, the wire strand 16 may have movement to the left of the gripping member 40 but movement to the right will be prevented by means of the tension applied to the bell crank 41 through the plunger 46 so that the sharp corner of the gripping member 40 will bite into the surface of the wire 16.

A second bell crank 50 is rockably mounted on a bolt 51 secured to the base plate 25 in spaced relation to the bell crank 41 and in a position adjacent the jaw or guide member 35. A gripping member 52 is adjustably secured as by a bolt or set screw 53 to one leg of the bell crank 50 in a position so that the wire engaging end 54 thereof will contact with the second or other strand of wire 16. The bell crank 50 is provided with one relatively long leg or arm 55 against which a spring pressed plunger 56 engages which is slidably carried by a housing or cylinder 57. The construction of the plunger 56 and the cylinder or casing 57 is similar in every detail to the plunger 46 and the cylinder or housing 47. A lubricating fitting 58 is provided in substantially the center of the base 25 so that a suitable lubricant may be passed through the base plate 25 in order to lubricate the operating lever 21 and the segmental members 23 which are disposed in the sockets 24 of the slide member 18.

In the use and operation of this device or machine, the rock lever or slide operating member 21 is rocked back and forth relative to the guide member 22 and as the pulling member 17 moves away from the straightening rollers 14, the several wire strands 16 are pulled therewith. At the time the pulling member 17 is pulling the wire over the rollers 14, the gripping members 12 are in spaced apart or released position and the hammer 11 is in a retracted or inoperative position. When the pulling member 17 moves to the left to the limit of its movement, the jaw members 12 are moved to engagement with the two wire strands 16 and the hammer 11 is moved to the right so as to strike the projecting ends of the strands 16 which project beyond or to the left of the gripping members 12. A head is thereby formed on the ends of the wires 16 and during the formation of the heads 59, the pulling member 17 is moving to the right with the wire strands 16 sliding along the jaw members 32 and 35 and beneath the gripping members 40 and 52. After the heads 59 have been formed on the ends of the wire strands 16, the hammer 11 is retracted and at the same time the gripping members 12 are moved laterally to a released position so that the pulling member 17 may pull the wire strands 16 forwardly so that the heads 59 will project beyond the gripping members 12 a distance substantially equal to the length of the 60 nails, screws or tacks which are thus being formed. The gripping members 12 are then moved to a gripping position and a pair of cutting dies 60 are moved toward the wire strands 16 so as to cut off the projecting headed wire 65 portions and at the same time form the point or shank of the article which is thus being formed. The knives or cutting members 60 engage the wire strands 16 at a point slightly beyond the gripping members 12 so that a small portion of 70 each wire strand 16 will project beyond the gripping members 12. This projecting portion 61 of the wire strands forms the head 59 upon impact of the hammer 11 therewith.

It will be apparent from the foregoing that 75

the conventional pulling member at present in use on the material forming machine may be removed and a pulling member constructed according to this invention may be substituted therefor together with grooved wire straightening members similar to the members 14. The gripping dies and the cutters capable of gripping and cutting the several wire strands are substituted for the gripping and cutting members at present in use and at the same time a hammer having a relatively wide head is inserted in place of the conventional hammer so that the head of the hammer will extend across the several wire strands projecting through the gripping members. In the present instance there are disclosed two wire strands so that the capacity of the machine may be doubled without the necessity of speeding up the working parts of the machine, but I do not wish to be limited to a structure showing only two wire strands as if desired two or more wire strands may be operated upon simultaneously, the pulling member and the straightening rollers 14 together with the gripping members 12, the cutting member 60 and the hammer 11 being so formed as to coincide with the number of wire strands used with this device.

What I claim is:

1. In a machine as set forth, a reciprocating pulling member comprising a base plate, an up-
30 standing flange at each end of said base plate provided with a plurality of spaced apart guide openings, a pair of upstanding lugs integral with said base plate, a fixed jaw member engaging one side of each lug, a right angularly disposed clamping plate engaging a jaw member and another side of a lug, means removably securing said plate on a lug, each jaw member being disposed with the gripping face thereof aligning with a guide opening, a pair of bell cranks, means rockably securing said bell cranks to said base plate, a movable jaw member carried by one arm of each bell crank in a position confronting a fixed jaw member, means removably securing a movable jaw member in said one arm of a bell crank, a pair of cylinders carried by said base plate, a plunger slidable in each cylinder engageable with the other arm of a bell crank, each of
40
45

said plungers having a reduced portion, a spring engaging about said reduced portion, and a nut engaging in an end of a cylinder and against an end of said plunger. 5

2. In a machine as set forth, a reciprocating pulling member comprising a base plate, a pair of upstanding lugs integral with said base plate, a fixed jaw member engaging one side of each lug, a right angularly disposed clamping plate 10 engaging a jaw member and another side of a lug, means removably securing said plate on a lug, a pair of bell cranks, means rockably securing said bell cranks to said base plate, a movable jaw member carried by one arm of each bell 15 crank in a position confronting a fixed jaw member, means removably securing a movable jaw member in said one arm of a bell crank, a pair of cylinders integral with said base plate, a plunger slidable in each cylinder engageable with the other arm of a bell crank, each of said 20 plungers having a reduced portion disposed interiorly of a cylinder, a spring engaging about said reduced portion, and a nut engaging in an end of a cylinder and against an end of said 25 spring whereby to tension said plungers.

3. In a machine as set forth, a reciprocating pulling member comprising a base plate, a pair of upstanding lugs integral with said base plate, a substantially L shaped jaw member engaging each lug, means removably securing a jaw member on a lug, a pair of bell cranks, means rockably securing said bell cranks to said base plate, a movable jaw member carried by one arm of each bell crank in a position confronting a fixed 30 jaw member, means removably securing a movable jaw member in said one arm of a bell crank, a pair of cylinders integral with said base plate, a plunger slidable in each cylinder engageable with the other arm of a bell crank, each of 35 said plungers having a reduced portion disposed interiorly of a cylinder, a spring engaging about said reduced portion, and a nut engaging in an end of a cylinder and against an end of said 40 spring whereby to tension said plungers. 45

JOSÉ DE JESÚS HERNÁNDEZ.
